UNITED STATES PATENT OFFICE.

SALMON THOMPSON AND WILLIAM E. FARRELL, OF MASONVILLE, IOWA.

MACHINE FOR MAKING BARBED-WIRE FENCING.

SPECIFICATION forming part of Letters Patent No. 254,516, dated March 7, 1882.

Application filed August 25, 1881. (No model.)

To all whom it may concern:

Be it known that we, SALMON THOMPSON and WILLIAM E. FARRELL, of Masonville, in the county of Delaware and State of Iowa, have 5 invented an Improvement in Machines for Making Barbed-Wire Fencing, of which the following is a specification.

The nature of this invention relates to certain new and useful improvements in the construction of machines to be employed in the manufacture of barbed-wire fencing, the object being to provide a machine which will secure the barbs upon the wire at stated intervals and form a burr or stud upon each side of the 15 barb in the one passage of the wire through the machine.

The invention consists, first, in the peculiar arrangement of gears employed in the operative parts of the machine; second, in the peculiar device whereby the barbs are separated; third, in the peculiar construction of the guide-wheels which embrace the wire and barb and hold the same while being operated upon by the burring-knife and hammer; fourth, in the 25 peculiar construction, arrangement, and various combinations of the parts, all as more fully hereinafter set forth.

Figure 1 is a perspective view of my improved machine. Fig. 2 is an enlarged perspective of a section of wire with the barb in place and as formed by my machine. Fig. 3 is a vertical cross-section on the line $y-y$ in Fig. 1. Fig. 4 is an enlarged perspective and a sectional view of the device employed for 35 separating the barbs.

In the accompanying drawings, which form a part of this specification, A represents a suitable frame to support the operating parts of the machine. Across this frame is properly 40 journaled the shaft B, by means of which motion is imparted to the several parts. At about the center of this shaft is properly keyed a broad pinion, C, Fig. 3, which engages with the crown-gear guide-wheels D, which in turn 45 are properly journaled upon the vertical studs a, which rise from the frame A. The faces of these wheels D are provided with an annular groove, E, and recesses b, which, in the rotation of the wheels D, embrace the barb and 50 present it to the hammer, as hereinafter set forth. Wheels G are mounted on bent arms secured to the frame A, so as to bear on the

outer edges of the upper surfaces of the wheels D, to keep them always horizontal and keep them constantly in gear with the pinion C.

Upon one end of the shaft is secured a proper pulley, F, by means of which and a belt the said shaft is driven from any proper power. Upon the opposite end of this shaft is secured a pinion, H, which, by a train of gear-wheels, I J K, imparts a rotary motion to the shaft L, to which is properly keyed a bevel-pinion, M, which in turn meshes with a similar pinion, N, which is properly secured upon a short hollow shaft, P, Fig. 4, properly journaled in the riser O, the center of such shaft P being in line with the point where the two wheels D come together. In the outer face of this bevel-pinion N is secured the divider R, said divider being constructed of two screw-plates, r, properly secured together, with a space between them, forming a hollow auger, as shown. The two plates r of the divider R are inserted one partly within the other, as shown in Fig. 4, and are secured together by studs r' near their peripheries, so as to leave sufficient space between them for the passage of one barb at a time, and to form two ends for separating the barbs on the wire. Two guide-wires, c, are secured at one end of the frame A, and project through the divider R and hollow shaft P back immediately over the wheels D, and are secured to the two risers S. The wire upon which the barbs are to be placed passes from end to end of the machine, between the guide-wires c, through the divider and hollow shaft, between the wheels D, and out between the risers S, as will be more fully hereinafter set forth.

Upon the upper face of each of the wheels D are secured, preferably adjustably, three cams, d, which in the rotation of the wheels elevate the trip-rods e, one end of each of which is pivoted to a block, h, secured to the studs a, while their outer ends come in contact with the rods T, which are pivotally secured to the frame, and raise their inner ends, which in turn come in contact with the yoke U, which carries the hammer V. In the continued rotation of the wheels D their respective cams pass from under the trip-rods, which releases the hammer from its elevated position, allowing it to fall upon the head of the double knife W, which is properly secured to the free ends of the springs X, which project forward from the

top of the risers S, the depth of cut of such knife W being regulated by stop-blocks *i* upon the top of the girt Y, which secures the two upper ends of the vertical studs *a* together.

5 A' represents trip-rods, which are actuated by the cams *d* upon the wheels D, for the purpose of raising at stated intervals the stop bar or rod B'.

In practice the wire upon which the barbs are to be placed is preferably wound upon a spool and hung in a suitable frame at the front end of the machine, and the barbs C' are strung upon this wire in a suitable number to provide the wire with barbs at certain distances apart its entire length. The end of the wire is then passed through the divider R and hollow shaft P, back to and between the wheels D, and thence back between the risers S, and is secured to another spool at the rear of the machine, both spools, if desired, being operated by belts from the machine in such a manner that it will be coiled upon one spool as fast as it is uncoiled from the other. As will be seen from the drawings, each of the wheels D is provided with six recesses for receiving the barbs, and with three cams for operating the trip-rods *e* and A', and these three cams are so arranged as to raise the trip-rods *e* and A' six times at each revolution of the wheels D. Motion now being imparted to the shaft B, and through it to the operating parts of the machine, the wheels are caused to rotate, while the divider D picks up one of the barbs upon the wire at each half-revolution and passes it through the hollow shaft P, the wire and barb advancing together until the barb comes in contact with the stop-bar B', where it remains during the advancement of the wire through the machine until the stop-bar is raised by means of the trip A', the movements of which are timed so that the barb will advance and be embraced by the recesses *b* of the wheels D as they come opposite to each other. At this point the trips *e* are timed so that the hammer will be raised and allowed to drop upon the knife W, which is driven down by such impact upon the wire, forming, as the knife straddles the bar, a burr or spur, *k*, upon each side thereof, and in the continued operation of the machine the barbs will be distributed along the wire and secured between the spurs *k* at equal distances apart, while the guide-rods *c* compel the barbs to advance to the divider and to the wheels D D in a vertical position.

55 What we claim as our invention is—

1. In a machine for making barbed-wire fencing, wherein the barbs to be placed upon such wire are strung upon the wire in a body, the divider R, by means of which the barbs are separated or picked up and passed to the operating parts of the machine, substantially as specified.

2. In a machine for making barbed-wire fencing, the wheels, D, rotating toward each other and provided with the recesses *b* and channel E, for the purpose of embracing the wire and barb and holding the same while it is being

operated upon, substantially as and for the purposes set forth.

3. In a machine for securing barbs upon wire, 70 constructed as described, the trip-hammer V and double knife W, in combination with and actuated by the wheels D and intermediate mechanism for the purpose of forming a spur in the wire upon each side of the barb, substantially as set forth. 75

4. In a machine for securing barbs on wire, the stop-bar B', in combination with the trip-rods A' and devices, substantially as described, for alternately raising said trip-rods, as and 80 for the purpose specified.

5. In a machine for barbing wire, the divider R, consisting of two intermeshing plates, *r r*, in combination with the hollow shaft P, to which it is secured, substantially as and for 85 the purpose specified.

6. In a machine for barbing wire, a rotating spiral divider provided with a central opening for allowing the passage of the fence-wire, and adapted to separate one barb at a time from a 90 series of barbs on said wire, substantially as described.

7. In a machine for barbing wire, and in combination with the divider R, stop-bar B', and the grooved and recessed wheels D, the guide-wires *c*, for the purpose of guiding the barbs through the machine, substantially as described. 95

8. In a machine for barbing wire, and in combination with mechanism, substantially as described, for feeding the barbs and wire, the double knife W, mounted on springs X X, and suitable means for striking said knife, as and for the purpose specified. 100

9. In a machine for barbing wire, the wheels 105 D, provided with grooves E, recesses *b*, and cams *d*, in combination with the trip-rods *e A'*, stop-bar B', rods T', hammer-yoke U, and mechanism, substantially as described, for imparting movement to the several parts, as and for 110 the purpose specified.

10. In a machine for barbing wire, the stop-bar B', in combination with the trip-rods A', the wheels D, provided with cams *d* for alternately operating the trip-rods, and mechanism, 115 substantially as described, for producing spurs on the fence-wire, as and for the purpose specified.

11. The wheels D D, rotating toward each other, and provided with recesses *b* and grooves 120 E, in combination with the cams *d*, secured to said wheels, the trip-rods A' *e*, the stop-bar B', the rods T, hammer-yoke U, hammer Y, double knife W, divider R, and connections, substantially as described, between the divider R 125 and the wheels D, as and for the purpose specified.

SALMON THOMPSON.
